UNITED STATES PATENT OFFICE.

FRANK J. BARNETT, OF WILKINSBURG, PENNSYLVANIA.

LATHE.

No. 858,358.

Specification of Letters Patent.

Patented June 25, 1907.

Application filed September 26, 1906. Serial No. 336,354.

To all whom it may concern:

Be it known that I, FRANK J. BARNETT, a citizen of the United States, residing at Wilkinsburg, in the county of Allegheny and State of Pennsylvania, have invented or discovered new and useful Improvements in Lathes, of which the following is a specification.

My invention relates particularly to lathes for automatically turning corks in imitation of champagne corks cut by hand. Such corks are required to have the sides more or less flat and the corners rounded.

It is the object of my machine to make such corks automatically from rectangular blanks and it involves mechanism for feeding the blanks to the chucks; for presenting the chucked blanks to the cutter; for cutting the corners round and the sides flat; for releasing the finished corks; and for resetting the chucks in position to receive a fresh blank.

While my machine is especially adapted for the work described, it may be utilized for cutting other shapes than that described by changing the shapes of the cams or by omitting the same. The tool may be a circular knife, as shown, or a fixed knife, a disk or cylinder composed of or covered with an abradant.

Referring to the drawings, Figure 1 is a central vertical section of my invention; Fig. 2, a similar section at right angles to the section of Fig. 1; Fig. 3, a plan thereof; Fig. 4, a section showing the machine support; Fig. 5, a detail section showing the means for tightening the feed belt; Fig. 6, a perspective of a finished cork; Figs. 7, 8, and 9, developments of the cam flange 15, the cam flange 36, and the cam 38, respectively; Fig. 10, a detail section, partly in plan, showing the device for causing the interrupted gearing to mesh; Fig. 11, an elevation looking toward the left on Fig. 2, the cutter being omitted; Fig. 12, an elevation looking toward the right on Fig. 2, the cutter being omitted; and Fig. 13, an elevation looking to the right on Fig. 11, the cutter being omitted.

On the drawings, 1 represents a vertical post like standard which supports a large part of the mechanism of my improvements. This standard may be supported in any desired manner, but I prefer to support it as follows: I provide a metal bar 2, having thereon the laterally-extending sleeve 3,

which is cut at 4 entirely through at one side where it has a pair of lugs 5 to receive the clamping screw 6. Within the sleeve 3 is the horizontal bar 7, which is held securely in any axial adjustment thereof by the screw 6 in an obvious manner. The bar 7 is provided with a vertical opening in which the standard 1 is secured in any desired vertical adjustment by the set-screw 8, and prevented from rotation by the key 9 seated in vertical slots in both the standard 1 and the bar 7. By this arrangement I can adjust the mechanism to compensate for the wear of the knife and for the requirements of the various shapes and sizes of the finished articles. The upper end of the standard 1 is supported by the stud-bolt 10, having one end screwed in the standard and the other end passed through the fixed bar 11, to which it is secured by the nut 12. The bar 11 may be secured to any suitable device which will hold the same stationary.

Fixedly secured to the standard 1 is the cam 13 prevented from rotation by the key 14 fitting in the standard and the cam. This cam has a vertical circular flange 15, whose upper or working face is shown developed in Fig. 7. It has a short deep portion 16 and a long, high portion with the three steps 17, 18, and 19, the first two of equal length and the third of a length equal to both the steps 17 and 18.

Loosely mounted on the standard 1 is the sleeve 20, to whose lower end is keyed the spur-gear 21. The lower face of the gear 21 has secured thereto by the screws 22 the support 23 for the horizontal pin 24, which carries the anti-friction roller 25, secured to the pin by the washer 26 and the screw 27. The roller 25 travels on the cam surface 15 and supports the sleeve 20 and all parts carried thereon. The hub of the gear 20 has secured thereto the eccentric disk or cam 28 having the depressed track 29 in its periphery and adjustable around the said hub by means of the set-screw 30.

On the sleeve 20 above the cam 28 is the spur-gear 31 adjustable on the sleeve by means of the set-screw 32. Seated on the sleeve 20 between the horizontal flange 33 at its upper end and the gear 31 is the cam 34, adjustable on the sleeve 20 by the set-screw 35. The cam surface is on the under side of the horizontal flange 36 and is shown developed on Fig. 8. It has the downwardly extending lug 37 which sharply descends to the

horizontal flange on one side and more gradually descends to the same on the opposite side. The cam disk 38 rests on the top of the sleeve 20 and surrounds the standard 1. The latter has the vertical slot 39 to receive the inner end of the screw 40 passed thereto through the periphery of the disk 38, thus preventing the rotation of the disk while permitting it to move vertically.

10 Loosely mounted on the standard above the disk 38 is the sleeve 41, on which the spur-gear 42 is rotarily adjustable by means of the set-screw 43. The lower face of the gear 42 carries the housing 44, in which is mounted the roller 45, which rides on the upper or working face of the cam 38. The said face of the cam is shown developed on Fig. 9. It has four elevations 46, corresponding to the four sides of a cork-blank, hereinafter to 20 be described. The sleeve 41 has the flange 47 which rests on the hub of the gear 42.

The loose ring 48 encircles the standard 1 and rests on the flange 47 and supports the sleeve-like projection 49 on the under side of 25 the table 50. Between the sleeve 49 and the standard is the bushing 51 which tapers upwardly and fits the correspondingly-shaped central opening of the sleeve. The sleeve has two vertical slots, through which pass 30 the bolts 53, which are screwed into the said bushing, and serve to clamp the sleeve and the bushing together in any vertical adjustment of the latter. By setting the bushing higher from time to time to take up the wear, 35 the table will be rigidly supported on the standard. The sleeve 49 and the bushing 51 have the slot 54 for the reception of the bolt 10 to permit the table 50 to rise and fall.

The driving shaft 55 is mounted on the 40 bracket 56 secured to the bottom of the cam 13 (see Fig. 1), and the bracket 57 secured to the bar 11 (see Fig. 3), and carries the long pinion 58 in mesh with the gear 21.

The vertical shaft 59 is mounted in the 45 bracket 60 secured to the bottom of the cam 13 and in the bracket 61 on the table 50, and carries the long pinion 62 in mesh with the gear 31, the long pinion 63' in mesh with the gear 42, and the bevel gear 64 in mesh 50 with the bevel gear 65 on the live spindle or shaft 66 which supports the chuck-head 67 and is mounted on the bracket 61. The gear wheel 31 has five times the circumference of the pinion 62, but has one-fifth of its teeth 55 omitted as shown on Fig. 10, so that the shaft 59 may rest during one-fifth of the rotation of the gear 31. In order that the gear 62 may be intergeared with the gear 31 after they have become disengaged, I have 60 secured the finger 63 to the top of the gear 31, which finger engages the rib 64 on shaft 59 sufficiently in advance of the time when the first tooth of the gear 31 reaches the pinion 62 as to cause the proper meshing of the 65 teeth.

The sleeve 49 carries the bracket in which are slidably mounted the two rods 65' and 66' connected together by the lever 67' having its pivot 68 between the rods. The rod 65' carries at its lower end the roller 69, 70 which cooperates with the cam 34. The upper end of this bar enters the table 50 and is provided with an adjustable collar which gages the vertical position of the roller 69, the collar resting against the bottom of the 75 table or the bushing 70 therein.

The bar 66' extends above the table 50 and engages the lower side of one end of the lever 71 mounted on the pin 72 on the table. The remaining end of this lever has its lower side 80 in engagement with the vertical pin 73, pressed upwardly by the spring 74. The lever 71 has the upwardly extending arm 75 which sits between the two adjustable collars 76 on the dead spindle or shaft 77 85 mounted on the bracket 78 on the table 50 and carrying the chuck-head 79. Above the chucks is the rotary knife 79', which may be revolved in any approved manner.

The standard 80 is secured to the bottom 90 of the cam 13 and has secured to its upper end by the bolts 81, the table 82. This table supports at one end thereof the horizontal shaft 83 having at one end the pulley 84 and at the other end the pulley 85. The 95 other end of the table 82 carries the pulley 86, adjustable by means of the screw 87 and the nut 88. The pulleys 84 and 86 are connected by the flat blank-feeding belt 89 whose upper side runs on the top of the 100 table 82 parallel with the length of the spindles 66 and 77. To the side of the table 82 is secured the bottom gage or rest 90 for the blanks, this gage being beneath the chucks and its surface in line with the top surface 105 of the belt.

91 is a blank pusher which slides on the plate 92 on the table 82.

93 is a side gage for the blanks, against which the belt 89 feeds them. It is secured 110 to the table 82 and supports the plate 95, carrying a roller 96, overlying the forward end of the pusher. The rear end of the pusher has secured thereto a flat spring 97 which rides beneath the roller and has a 115 sharp downward bend 94 just at the rear of the roller when the pusher is in its retired position. The pusher moves at a right angle to the belt 89. The pusher is actuated by the vertical lever 98 mounted on the pivot 99. 120 On the lower end of the lever 98 is pivoted the arm 100, carrying the roller 101 which rides in the cam track 29. The lever 98 is in two parts, the upper part 102 being mounted on the pivot 103 on the lower part. The lower 125 end of the upper part has secured thereto the rod 104 which passes through the standard 80 and has thereon the coil spring 105, seated between the standard and the nut 106 on the rod. A set-screw 107 passes through the 130

lower end of the part 102 and engages the lower or fixed part of the lever 98, in order to adjust the position of the pusher which is pivotally connected to the upper end of the lever 98.

The table 82 is provided with the side strips 107 and 108 on opposite sides of the belt 89, one gage, as 108, being adjustable to accommodate different sizes of blanks. This table also carries the two idle pulleys 109 and 110 and the table 50 carries the idle pulleys 111 and 112, and the shaft 55 carries the driving pulley 113. The belt 114 runs over the pulley 113 and then the pulleys 110, 85, 109, and 111 and back to the pulley 113. This belt drives the belt shaft 83. The bar 11 has the slot 115 for the bolt 10, so that the standard 1 may be swung on the bar 7, if desired, in the adjustment of the machine. 116 is the gage against which the pusher 91 delivers the blanks. It is secured adjustably, both vertically and horizontally, on the bolt 10.

We will assume that the roller 25 is in the lowest portion in the track or cam surface 15 of the cam 13 and that the pinion 62 is opposite the untoothed portion of the gear 31. The sleeve, the gear 21, the cam 28, the gear 31, the cam 34, the cam 38, the sleeve 41, the gear 42, the table 50 and the chucks 67 and 79 will all be lowered, when the chucks will come to rest at such a position above the rest 90 as to be opposite a blank on said rest. The lowering of the cam 28 causes the rocking of the arm 100 on the lever 98 by reason of the action of the recessed track on the roller 101, the periphery of the roller and the upper wall of the track being beveled to permit such rocking. The cam portion 37 of the flange 36 on the cam 34 will be on the roller 69, causing the chuck 79 to move away farther from the chuck so as to allow a blank to be received between them. Upon the starting of the driving shaft 55, the conveyer belt 89 will cause a cork blank deposited thereon to be delivered in front of the pusher 91 and against the gage or side piece 93. The cam 28 operates then to cause the lever 98 to rock and move the pusher 91 toward the chucks. A slight movement of the pusher brings the bend 94 of the spring 97 under the roller 96, causing the spring to press slightly on the blank to keep it in place to be passed properly between the chuck-heads and against the gage 116. The pressure of the spring continues on the blank all the way to the gage 116, owing to the horizontal portion of the spring at the rear of the bend 94. The cam projection 37 of the cam 34 now passes from the roller 69, permitting the spring 74 to move the chuck 79 against the end of the blank so as to clamp the same firmly between the chucks. The cam 28 then permits the spring 105 to move the pusher and the spring 97 away from the blank. The roller 25 then

rides up from the depression 16 to the step 17, causing the table 50 together with the chucks to rise. After the chucks have lifted the blank free from the bed 90, the gear 31 engages the pinion 62, causing the rotation of the chucks and the blank. The knife 79 being already in rotation cuts off the corners of the blank which is square in cross-section to the depth permitted by the step 17. During the cutting operation the cam 39 is moving the table 50 slightly up and down. This is for the purpose of cutting the corners of the blank round, while the sides are left flat or nearly so. When the roller 45 is on the elevations 46, the table is raised and the knife 79 cuts nearer the center of the blank; and when the roller is between the elevations, the knife cuts farther from the center of the blank. In the former position of the roller, the sides of the blank are being cut; and in the latter, the corners are being cut. When the shaft 59 and therefore the blank has made one revolution, the cam roller 25 rides upon the step 18 and a deeper cut is made in the blank during another rotation thereof. After the completion of the second rotation the roller rides up on the step 19, causing the knife to take a still deeper cut which is the finishing cut. The blank has two rotations while the roller is on the step 19. Just before the cam 25 is ready to descend to the depression 16, the cam piece 37 of the cam 34 depresses the roller 69, whereupon the chuck 79 retires and releases the finished cork. Also the rotation of the chucks has been stopped by the disengagement of the gear 31 and the pinion 62. The roller 25 now rides down in the depression 16, causing the chuck to be lowered ready to receive another blank pushed between them by the pusher 91.

Fig. 1 shows the cam projection 37 close to the roller 69 ready to open the chucks, and the roller 25 a short distance from the depression 16 ready to descend into the same as soon as the projection 37 has opened the chucks.

I do not restrict myself to the precise details and combinations shown and described.

I claim—

1. In a lathe, a cutting tool, a vertical stationary post-like standard, a chuck-table vertically movable thereon, a feeding device to present the blanks to the chucks, a chuck opening and closing device, and cams sleeved on said standard for raising and lowering said table to present the blanks in the chucks to the cutting tool, for controlling the opening and closing of the chucks, and for controlling the blank feeding device in combination with means for intermittently rotating the chucks.

2. In a lathe, a vertical fixed standard, a stationary cutting tool, a feeding device below said tool, a pair of chucks, a chuck-table movable vertically on said standard to carry

- the blanks from the feeding device to the cutting tool, a sleeve slideable on said standard, and a cam on said standard, said sleeve and cam co-operating for raising said table to carry the blanks to the cutting tool.
3. In a lathe, a vertical fixed standard, a stationary cutting tool, a feeding device below said tool, a pair of chucks, a chuck-table movable vertically on said standard to carry the blanks from the feeding device to the cutting tool, and means vertically reciprocable and sleeved on said standard for raising said table to carry the blanks to the cutting tool.
10. In a lathe, a vertical fixed standard, a stationary cutting tool, a feeding device below said tool, a pair of chucks, a chuck-table movable vertically on said standard to carry the blanks from the feeding device to the cutting tool, a sleeve on said standard, a cam on said standard and co-operating with the sleeve for raising said table to carry the blanks to the cutting tool, and means also sleeved on said standard for raising and lowering said table during the cutting operation.
15. In a lathe, a vertical fixed standard, a stationary cutting tool, a feeding device below said tool, a pair of chucks, a chuck-table movable vertically on said standard to carry the blanks from the feeding device to the cutting tool, a sleeve on said standard, a cam on said standard and co-operating with the sleeve for raising said table to carry the blanks to the cutting tool, and means also sleeved on said standard for raising and lowering said table during the cutting operation.
20. In a lathe, a vertical fixed standard, a stationary cutting tool, a feeding device below said tool, a pair of chucks, a chuck-table movable vertically on said standard to carry the blanks from the feeding device to the cutting tool, means sleeved and slideable vertically on said standard for raising said table to carry the blanks to the cutting tool, and means sleeved on and rotatable about said standard for opening and closing the chucks.
25. In a lathe, a fixed vertical standard, a chuck - carrying table movable vertically thereon, a cutter to which the chucks on said table present the blanks to be cut, a sleeve encircling said standard, and a cam on said sleeve adapted to raise and lower said table during the cutting operation to vary the depth of the cut.
30. In a lathe, a fixed vertical standard, a chuck - carrying table supported thereon, a cam rotatable around said standard, a feeding table, means on said table to place the blanks between the chucks, and operating connections between said cam and said placing means.
35. In a lathe, a fixed vertical standard, a pair of chucks supported thereby, a cam rotatable around said standard as a center, a lever for closing the chucks, a pair of reciprocable rods, one being in engagement with said lever to actuate the same and the other being operatively connected to said cam, and a rocking lever connecting said rods.
40. In a lathe, a fixed vertical standard, a stationary cutter, a blank feeder below the cutter, two sleeves rotatable and slideable on the standard, a pair of chucks, a table supported by the sleeves, slideable on the standard, and supporting the chucks, means for raising both sleeves to cause the chucks to raise a blank from the feeding device to the cutter, and means for independently raising and lowering the upper sleeve to vary the depth of the cut of the cutter in the blank.
45. In a lathe, a fixed vertical standard, a stationary cutter, a blank feeder below the cutter, a pair of chucks, a table supporting the chucks and slideable on the standard, means on the standard for raising the chucks with a blank from the feeding device to the cutter, and other means on the standard for varying the depth of the cut in the blank.
50. In a lathe, a fixed vertical standard, a pair of chucks, a chuck-supporting table movable vertically on said standard, means for opening and closing the chucks, means rotatable on the standard for raising and lowering the chucks, a shaft for rotating the chucks, a driven gear thereon, a driving gear rotatable and slideable on said standard and meshing with the said driven gear, a portion of the teeth on the driving gear being omitted, and means on said two gears to advance the driven gear so that both gears may accurately mesh when the first tooth of the driving gear engages the driven gear.
55. In a lathe, a vertical standard, a chuck - carrying table vertically movable thereon, a sleeve slideable and rotatable on said standard for raising and lowering said table, a cam secured to said sleeve, a feeding device to present the blanks to the chucks, a lever to operate the feeding device, and a connection between said cam and said lever movable up and down in operative engagement with said cam as the latter rises and sinks with the sleeve.
60. In a lathe, a vertical standard, a chuck - carrying table vertically movable thereon, a sleeve slideable and rotatable on said standard for raising and lowering the table, a cam secured to said sleeve, a feeding device to present the blanks to the chucks, a lever to operate the feeding device, a connection between said cam and said lever movable up and down in operative engagement with said cam, and means permitting the lower end of the lever to move while the other end remains stationary.
- Signed at Wilkinsburg, Pa., this 22nd day of September, 1906.
